GARAGE DOOR EQUIPMENT

William D. Ferris and Cecil R. Wolf, Sterling,
Ill., assignors to Frantz Manufacturing Co.,
Sterling, Ill., a corporation of Illinois

Application September 8, 1941, Serial No. 410,028

12 Claims. (Cl. 20—19)

1

This invention relates to closing and opening means for doors of the type generally known as garage doors, although the invention is of broader application where peculiarly adaptable therefor.

Among the objects of the present invention is to provide closing and opening means for garage doors of the rigid door type, wherein the door is substantially vertical when closed, and in substantially horizontal overhead position when open, and wherein the frame forming the openings for the doors is provided with more or less horizontally disposed track means and the door is provided with rollers adapted to run on said track means, and wherein the door is provided with a pair of arms pivoted thereto, the opposite ends of said arms being pivoted to stationary anchorages fixed to the side frame of the door on two suitable stationary brackets within the enclosure formed by the door frame.

In this type of door it is the object of the present invention to provide a door stop holder adapted to engage the pivoted arms interconnecting the door with the door frame so as to prevent the door from opening too far and more specifically to provide means for holding such pivoted arms when they are in the open overhead position whereby to prevent the door from opening too far; to provide, in association with a door of the one-piece type, means for automatically swinging the door from a closed vertical position to an open overhead position immediately the door is unlocked, and wherein a door checking means is provided to act in cooperation with the swingable pivoted lever which pivotally connects the lower portion of the door with a bearing on a stationary abutment, wherein the means operates on the lever to first check the momentum of the moving door as it moves to open position whereby to slow down the door, and thereafter positively prevents further movement of the door beyond a predetermined position, and in addition provides means to prevent the door rolling back out of the opening after it has once reached full open position; to provide a device of the foregoing nature which when properly adjusted assists in guiding the levers of the door and the door so that there will be no contact between the door and the door jamb during the opening and closing movements of the door; to provide a door check for a door of the foregoing character formed of spring metal and bent in such a manner as to provide a snubbing portion for slowing down the momentum of the door as it approaches full open position

and thereafter yields to let the door continue at a slowed down pace to full open position, and at which time an absolute check is provided for preventing the door going past full open position, said last mentioned positive door check being constructed in such a manner that the checking and the complete stoppage of the door is accomplished without deforming the door check itself; to provide a door check for a door of the foregoing character which has four functions, to-wit, checking the speed of the door, stopping the door, preventing the door rolling outwardly again after being stopped in open position, and lastly to maintain clearance between the door and the jamb; to provide an adjustment for this arm holding means so that it may contact the arms with sufficient pressure to produce the necessary friction for deadening the tendency of the door to rebound when the arm strikes the stop; to provide a pivotal connection between the swinging lever of the door and the bottom of the door whereby all binding between the door and jamb is eliminated and the smooth rolling of the door wheels in the overhead tracks is assured, and whereby there is included also the perfect positioning and locating of all the important pivotal points in the door hardware and its proper operation and action is effected; still another object of the present invention is to provide a door of the foregoing construction which provides substantially perfect positioning of the arm lever pivots, the overhead track and the upper and lower weatherstrips so as to allow substantially perfect freedom of door action, and in addition to provide means which in association with the pivotal connection of the lever arm with the lower portion of the door whereby in the closed position of the door the weight of the door is removed from the lever arm and applied solely to the overhead track mechanism, and alternatively which pivotal connection in the open overhead position of the door is arranged so as to maintain the door in full open position and prevent it from rebounding or moving outwardly toward downward closed position; to provide means tending to prevent any binding action at the so-called breaking point of the door when the door is operated; to provide means to prevent or restrain the movement of the arm relative to the connection at the outer end of this arm with the door when the door is in open overhead position, while at the same time permitting the weight of the door to be carried by the track and roller means and not by the arms when the

door is in closed position; to provide in a door of the foregoing character an arrangement of spring and lever construction so that the arm or lever is located with relation to the spring when the door is in closed position so as to provide sufficient force to start the door outwardly and upwardly automatically when the spring catch holding the door in closed position is released, whereby the opening position of the door is substantially automatic and whereby this so-called self-starting movement in the opening of the door will eliminate the uncertainty of the door opening too fast or too slow as in the case when it is required to manually lift upon the door to give it its initial opening movement; to provide a simple type of stop mechanism for limiting the extreme opening position of the door and to provide in association therewith a snubbing action to prevent rebounding of the door after the door hits the stop during the completion of the opening movement; to provide these and other objects of the invention as will be apparent from a perusal of the following specification, taken in connection with the accompanying drawings, wherein:

Figure 1 is a vertical sectional view taken on the line 1—1 of Figure 2, showing the door in closed position;

Figure 2 is an inside view of the door taken on line 2—2 of Figure 1;

Figure 3 is a vertical sectional view showing the door in open position;

Figure 4 is a perspective view of the operating mechanism when the door is in closed position;

Figure 5 is a perspective view of the operating mechanism when the door is in open position;

Figure 6 is a perspective view of the right-hand lower bracket which interconnects the outer end of the pivoted arm or lever and the door;

Figure 7 is a plan section taken on line 7—7 of Figure 5;

Figure 8 is a detailed section view taken on line 8—8 of Figure 4;

Figure 9 is a detailed section view taken on line 9—9 of Figure 8.

Referring now to the drawings in detail, the invention is illustrated in connection with an enclosure of any desired type, preferably a garage having a frame 2 providing an opening, the roof of the garage being shown at 4. At the top the garage is provided with tracks 6 which are preferably inclined downwardly from front to rear for the purpose of eliminating the tendency of the door to come back slightly after it reaches the complete overhead position. The door 8 is preferably of the rigid one-piece type and is adapted when closed to be in substantially vertical position with respect to the frame opening as shown in Figures 1 and 4, and to be in substantially overhead open position, as shown in Figures 3 and 5.

The upper front corners of the door are provided with a bracket 10 which carries an angularly disposed ear 12 on which is pivotally mounted as at 14 a roller 16 adapted to run in the track 6. It is understood that there are rollers on each side of the door and tracks on each side of the door frame whereby the upper rear opposite corners of the door are supported by the track 6.

In cooperation with the tracks 6 and the rollers 16, are provided means for pivotally supporting the doors so as automatically to cause them to swing from the substantially vertical closed position upwardly and outwardly to a substantially

horizontal overhead open position when the door is unlatched. This means comprises a pair of brackets 18 which are secured as at 20 to a metallic reinforcing weatherstrip 22 rigidly mounted on the vertical frame 24 at and slightly overlying opposite sides of the door opening. The outer rear face of this bracket carries a mounting member 26 secured thereto by means of the bolts 28, which mounting is provided with an outwardly extending bearing 30 in which is rotatably mounted a short pivotal pin 32, on one end of which is pinned a relatively long arm or lever 34 and to the opposite end of which is pinned a relatively short lever or arm 36. The lever arms 34 and 36 are arranged to swing with the turning of the pivotal pin 32 as the latter rotates in its bearing 30. In short, as the lever 34 swings upwardly with the turning of the pin in its bearing 30, the short arm 36 likewise swings an equal number of degrees.

Means is provided for pivotally connecting the outer end of the long lever 34 to the door 8. This means comprises the bracket 40 shown in Figure 6. This bracket is preferably formed

25 L-shaped and comprises a flange 42 adapted to be fastened to the door by means of screws or the like and a right-angle flange 44 having an elongated slot 46 and a laterally extending lug 48 projecting from the free edge of the flange 44.

30 A pivotal pin 50 connected to the outer end of the lever or arm 34 is adapted to slide in the slot 46. When the door is in lowered position the arm 34 does not contact the lug 48. However, when the door is in open overhead position the arm 34 will contact this lug 48 for a purpose hereinafter made evident.

35 A relatively long coil spring 52 has one end thereof fastened by means of a pin 54 to the outer end of the short arm 36 and the opposite end of the coil spring 52 is provided with an anchorage 56 engaging a rod 58 which passes through an inclined portion 60 of a bracket fastened to the frame member 24. The upper portion of this bracket is provided with a substantially horizontal face or ledge 64, through which the free end of the rod 58 passes. A nut 66 adjustably holds the rod 58 with respect to the bracket, whereby the tension of the spring may be adjusted. The vertical stationary member 62 is a part of the doorway frame.

40 Means is provided in association with the arms 34 for checking the speed of the door as it approaches full open position, and for thereafter absolutely stopping the door at full open position, for preventing the door rolling reversely or outwardly and downwardly towards closed position, and for maintaining clearance between the door and the door jamb. In the door construction forming the subject matter of this invention the levers of the arm 34 and the spring means are so disposed as to cause the door to open automatically when the latch is released without the operator giving the door a preliminary outward or lifting movement. Due to the fact that the present construction is devised so that the door will automatically open when once unlatched, the effectiveness of the lever and the spring power for holding the door in open position is somewhat sacrificed. Therefore to hold the door in open overhead position and to prevent its rolling back because of the reduced spring power and leverage at the open position, a door check mechanism is used which cooperates in a multifold manner with the lever mechanism to produce a plurality of results. The check means not only supplies a

holding means to prevent the door rolling back out of the open position, but also acts to change the speed and momentum of the door as it reaches open position, as well as to positively check further movement of the door after the speed of movement of the door has been reduced. In addition, the door check, when once properly adjusted, assists in guiding the arm levers and the door so that no contact is possible in open position between the door and the door jamb. It is practically impossible to obtain rigidity enough in the arm levers and the bearing to obtain such results without the door check, and the door check accomplishes these results very easily. The door check means comprises a bracket 70 having a slotted outer end 71 for adjustable attachment to the framework of the door, the adjustment being accomplished by means of a suitable bolt 72 passing through the slot and engaging the stationary frame of the door or any other fixed support. The outer end of this bracket is bent forwardly to provide a friction surface 74 and is also provided with a somewhat angularly bent holding portion 76 which terminates in an angularly disposed flange 78 to receive the arm 34. This bracket is preferably formed of resilient metal and is arranged so that as the arm swings upwardly the arm is adapted to engage the portion 74 and force the same laterally with sufficient pressure to produce friction, which thus deadens the tendency of the arm to rebound when the arm strikes the usual door stopping member. By laterally adjusting this bracket 70, the friction pressure may be adjusted to control this deadening effect.

The door check means thus not only supplies a holding means to prevent the door rolling back out of the opening, but also acts to check the speed and momentum of the door as it approaches the open position. In this connection it is desired that the shape of the door check is of particular construction. For instance, by reference to Figure 7 it will be seen that the portion 74 on the door check contacts the arm lever 34 more severely than at the balance of the straight portion of the check as at 76 in Figure 7. After the arm levers, because of momentum, have forced their way past the point 74, the arm levers cannot return past the high point 74 on the door check. In addition, the door check is made so that it has a substantial flexibility of action so as not only to permit the high portion 74 to be shifted laterally so as to permit the arm 32 to move therewith, but also so that when the arm 34 strikes the pocket in the stop portion 78 the impact will be taken up in the resiliency of the spring metal arm or bracket as a whole. In addition the slot 71 in the door check provides an easy method of adjusting the severeness of engagement between the door check and the lever arms 34.

Furthermore, the door checks, when properly adjusted, tend to guide the arm levers and door so that no contact is possible in open position between the door and the door jamb. This function of the door check is accomplished very easily as otherwise it would be nearly impossible to obtain rigidity enough in the arm levers and their bearings to obtain such results. When the arm lever moves into the door check with sufficient force that it reaches the end 78, as shown in Figure 7, the arm encounters a positive resistance preventing the door going back beyond predetermined open position. The shape of the door check is important for it is the closed end 78 of

the check which provides a positive resistance for preventing the door going past full open position and the shape of the entire door check and its construction is important for it is the closed end shape of the door check which is contacted by the arm, and therefore because of the bent end shape of the door check the arm cannot spring the flexible door check out of the way and continue, but is stopped quite firmly at this point. Thus if the door action is abrupt enough the door check actually does spring away some, but the end of the door check which is bent over to hold the arm lever also pulls the arm lever with it so that even a very violent action of the door is brought under control by the very flexibility built into the door check and without causing the door check to be bent out of shape.

The spring power at this point is without leverage because of the pull required of the spring to start the door opening and hence there is no tendency of the spring to pull the door back to closed position when in this position, shown in Figure 4. On the contrary, by reference to Figure 8, which represents the closed position of the door, it will be seen that the center of the pin 54 in the closed position of the door is to the left of a vertical line 9-9 passing through the center of the pin 32 and the pin 54, whereby the spring which is connected around the pin 54 and which is constantly under tension in this position is always tending to open the door. Therefore, as soon as the usual latching means on the door is unlatched, this spring is immediately operative automatically to raise the door to overhead open position and as the door approaches extreme open position, as shown in Figure 5, the spring itself will assume a contracted position and will not be under tension sufficiently to tend to move the door downwardly again.

It will be noted that the angularly disposed portion 78 of the check definitely forms a stop for the upward position of the arm 34 to limit the overhead position of the door.

It will also be noted by reference to Figure 1 that in the closing and then in the closed position of the door the pin 50 is sequentially in the central portion of the slot 46 of the bracket 42 on the door and then in the bottommost end of the slot respectively in either of which positions the weight of the door is not borne by the arm 34. Thus, in the closing and closed positions, the weight of the door is carried on the roller 16 and on the track 6.

However, in the open or overhead position of the door this same slotted arrangement is disposed in conjunction with the lug 48 so that as the lever 34 swings to upward position as shown in Figure 3 the left edge of the lever will contact the lug 48 so as to prevent or restrain the movement of the pin 50 in the slot when the door is in overhead position, retains the pin in the right hand end of the slot 46 as shown in Figure 3, which is the upper end of the slot when the door is in closed position. This prevents the door from again moving or rebounding outwardly beyond the position shown in Figure 3 toward closed position by limiting and preventing movement of the door to the left in Figure 3 relative to the pin 50 on the upper end of the arm 34. The slot and pin connection between the door and the lever 34 also prevents any binding action at the breaking point when the door is operated.

The main purpose of the slotted plate 44, including the slot 46 and the lug 48 is to allow proper operation and action of the hardware.

For instance, it is virtually impossible to obtain an absolutely perfect positioning of the pivot 32 of the arm lever 34, the pivots 50, the overhead track, the upper weatherstrip 10, and the lower weatherstrip or steel stop 22 so as to allow perfect freedom of door action. The location of all these points must be exact, and in the present construction it cannot be done because the main bearing or pivot 30 of the arm lever must be positioned inwardly away from the door jamb 24 so that the short lever arm 36 may clear the door jamb as the arm swings arcuately. Consequently if an ordinary hole or aperture were employed in the door plate brackets 40, the hanger wheels 16 would be forced upwardly against the top of the rail or track 6 when the door was being opened. However with the flexibility in the construction of the slotted door plate bracket 40, the wheels 16 roll smoothly in the bottom of the track as distinguished from the top, and the upper and lower weatherstrips 10 and 22 respectively do not bind on the door or jamb. Without this construction the smoothness and good balance of the equipment could not be obtained and the hardware would be impractical to operate, due mainly to the substantial impossibility of obtaining perfect positioning of all important pivotal points without the use of the slot 46 and its cooperating elements. The lug 48 on the door plate 40 assists in keeping the stud 50 in the correct location when the door is approaching open position, in the manner hereinbefore described.

It will be noted by reference to Figure 1 that the lever 34 is located in relation to the pull of the spring 52 when the door is closed so as to provide sufficient force to start the door 8 outwardly and upwardly automatically the instant the spring latch for the door is unlocked or released so that the opening operation of the door is practically automatic and therefore differs from the construction of most doors of this type which require a manual initial movement of the door to start the door into upward movement and this starting action also eliminates the uncertainty of the door going open too fast or too slow as in the case when hand starting is required as hereinbefore set forth.

Obviously the invention is not limited to the specific forms disclosed herein but is capable of other modifications and changes without departing from the spirit and scope of the claims appended hereto.

The invention is hereby claimed:

1. In combination with an enclosure having a frame providing a door opening, a rigid door therefor adapted in vertical position to close said opening and adapted to swing bodily to a substantially horizontal overhead open position, interengageable track and roller means connected to said frame and door, a stationary support mounted to the rear of said door when the latter is in closed vertical position, an arm having an axis of turning disposed to the rear of said door when in vertical position, said arm having at its outer end a turnable pivotal connection with said door, spring means interconnecting said door with a stationary abutment on said frame tending to shift said door from a closed position to an open position and stop means disposed in the arcuate path of movement of said arm and having a portion adapted to be engaged by said arm for positively limiting the extreme opening movement of said door, said stop means having a portion adapted frictionally to be engaged by said arm

as the door approaches said stop means, whereby to effect a preliminary snubbing or dampening action on the movement of said arm as said arm approaches extreme door opening position, said latter portion being shiftable out of the path of movement of said arm to permit said arm to engage said first mentioned portion of said stop means, and said last mentioned means being operative to prevent rebounding of the door outwardly after contacting said first mentioned portion of said stop means.

2. In combination with an enclosure having a frame providing a door opening, a rigid door therefor adapted in vertical position to close said opening and adapted to swing bodily to a substantially horizontal overhead open position, interengageable track and roller means connected to said frame and door, a stationary support mounted to the rear of said door when the latter is in closed vertical position, an arm having an axis of turning disposed to the rear of said door when in vertical position, said arm having at its outer end a pivotal connection with said door, spring means interconnecting said door with a stationary abutment on said frame tending to shift said door from a closed position to an open position and stop means including a portion disposed in the path of movement of said arm and adapted yieldably to engage a portion of said arm, whereby preliminarily to check the movement thereof, said portions being shiftable out of the way of said arm, said stop means including an additional portion adapted to lie directly in the path of movement of said arm whereby after said checking action absolutely to preclude further movement of said arm beyond a predetermined position, and said last mentioned means being operative to prevent rebounding of the door outwardly after contacting said first mentioned portion of said stop means.

3. In combination with an enclosure having a frame providing a door opening, a rigid door therefor adapted in vertical position to close said opening and adapted to swing bodily to a substantially horizontal overhead open position, interengageable track and roller means connected to said frame and door, a stationary support mounted to the rear of said door when the latter is in closed vertical position, an arm having an axis of turning disposed to the rear of said door when in vertical position, said arm having at its outer end a pivotal connection with said door, spring means interconnecting said door with a stationary abutment on said frame tending to shift said door from a closed position to an open position, and a spring metal stop means disposed in the path of movement of said arm and having a portion yieldable out of the path of movement of said arm to permit continued but checked movement of said arm, said stop means including a further portion directly in the path of movement of said arm to provide a positive stop therefor, and said last mentioned means being operative to prevent rebounding of the door outwardly after contacting said first mentioned portion of said stop means.

4. In combination with an enclosure having a frame providing a door opening, a rigid door therefor adapted in vertical position to close said opening and adapted to swing bodily to a substantially horizontal overhead open position, interengageable track and roller means connected to said frame and door, a stationary support mounted to the rear of said door when the latter is in closed vertical position, an arm having an

axis of turning disposed to the rear of said door when in vertical position, said arm having at its outer end a pivotal connection with said door, spring means interconnecting said door with a stationary abutment on said frame tending to shift said door from a closed position to an open position, and spring metal stop means disposed in the path of movement of said arm and having a portion yieldable out of the path of movement of said arm to permit continued but checked movement of said arm, said spring metal stop means comprising an arm adjustable laterally with respect to the path of movement of said first-named arm, whereby to provide a variation in the frictional engagement of said first-named stop means with said arm as the door approaches its open position.

5. In combination with an enclosure providing a frame forming a door opening, a rigid door adapted to be associated with said frame to close said opening when the door is in substantially vertical position, said door being shiftable bodily to a substantially horizontal overhead open position, bracket means disposed on the inside portion of said frame, said bracket means including a pivotal bearing, an arm having an axis of turning in said pivotal bearing, said arm at its outer end being pivotally connected to the lower portion of said door, a substantially horizontal track for the upper portion of said frame and roller for the upper portion of said door adapted to run in said track, spring means having one end connected to a stationary abutment and operatively connected to said door to tend to swing the door to open overhead position from closed position and stop means mounted on said frame adjacent and above said bracket, said stop means having its inner end disposed vertically above the pivotal bearing and lying within the path of movement of said arm as said arm approaches the position in which the door is in overhead open position, whereby to limit said open position of the door, said stop means having a portion yieldably to engage the side of the arm to check the closing movement of the door prior to the complete stoppage thereof and to prevent lateral swaying of the door during opening or closing movement.

6. In combination with an enclosure having a frame providing a door opening, a rigid door therefor adapted in closed position to lie substantially vertical and to shift to substantially horizontal overhead open position, substantially horizontal track means on the upper portion of said frame, roller means on said door adapted to run in said track means, a relatively long arm, means providing at one end of said arm an axis of turning therefor located to the rear of said door when the door is in closed position, spring means having one end associated with a stationary abutment disposed to the rear of said door when the door is in closed position and having the other end operatively associated with said door to assist in opening said door, means pivotally interconnecting the outer end of said arm and said door including a slot and pin connection therebetween arranged so that when the door is in closed position the pin will be at a point in said slot removed from the upper end of said slot whereby to remove the weight of said door from said arm, and means operative only in the open position of the door for preventing relative bodily shifting movement between the pivotal connection at the outer end of the long arm and the door.

7. In combination with an enclosure having a

frame providing a door opening, a rigid door therefor adapted in closed position to lie substantially vertical and to shift to substantially horizontal overhead open position, substantially horizontal track means on the upper portion of said frame, roller means on said door adapted to run in said track means, a relatively long arm, means providing at one end of said arm an axis of turning therefor located to the rear of said door when the door is in closed position, spring means having one end associated with a stationary abutment disposed to the rear of said door when the door is in closed position and having the other end operatively associated with said door to assist in opening said door, means pivotally interconnecting the outer end of said arm and said door including a slot and pin connection therebetween arranged so that when the door is in closed position the pin will be at a point in said slot removed from the upper end of said slot whereby to remove the weight of said door from said arm, said connection including stop means associated with the arm to prevent said pin moving in said slot in the open overhead position of the door.

8. In combination with an enclosure having a frame providing a door opening, a rigid door therefor adapted in closed position to lie substantially vertical and to shift to substantially horizontal overhead open position, substantially horizontal track means on the upper portion of said frame, roller means on said door adapted to run in said track means, a relatively long arm, means providing at one end of said arm an axis of turning therefor located to the rear of said door when the door is in closed position, spring means having one end associated with a stationary abutment disposed to the rear of said door when the door is in closed position and having the other end operatively associated with said door to assist in opening said door, means pivotally interconnecting the outer end of said arm and said door including a slot and pin connection therebetween arranged so that when the door is in closed position the pin will be at a point in said slot removed from the upper end of said slot whereby to remove the weight of said door from said arm, said connection including means operative only when the door is in overhead position to maintain said pin at the upper end of said slot.

9. In combination with an enclosure having a frame providing a door opening, a rigid door therefor adapted in closed position to lie substantially vertical and to shift to substantially horizontal overhead open position, substantially horizontal track means on the upper portion of said frame, roller means on said door adapted to run in said track means, a relatively long arm, means providing at one end of said arm an axis of turning therefor located to the rear of said door when the door is in closed position, spring means having one end associated with a stationary abutment disposed to the rear of said door when the door is in closed position and having the other end operatively associated with said door to assist in opening said door and means providing a pivotal connection between the outer end of said arm and said door including a slot and pin connection operative when the door is in vertical position to remove the pin from that end of the slot in which position the weight of the door will be carried by said arm, said last motion connection including means operative

11

only when the door is in overhead position to maintain the pin at such aforesaid end of the slot.

10. In combination with an enclosure having a frame providing a door opening, a rigid door therefor adapted in closed position to lie substantially vertical and to shift to substantially horizontal overhead open position, substantially horizontal track means on the upper portion of said frame, roller means on said door adapted to run in said track means, a relatively long arm, means providing at one end of said arm an axis of turning therefor located to the rear of said door when the door is in closed position, spring means having one end associated with a stationary abutment disposed to the rear of said door when the door is in closed position and having the other end operatively associated with said door to assist in opening said door and means providing a pivotal connection between the outer end of said arm and said door including a slot and pin pivotal connection between the arm and the door and operative when the door is in vertical position to permit movement of the pin vertically downwardly in the slot so as to remove the weight of the door from the arm and including means for preventing relative movement between the slot and the pin only when the door is in overhead substantially horizontal position.

11. In combination with an enclosure having a frame providing a door opening, a rigid door therefor adapted in closed position to lie substantially vertical and to shift to substantially horizontal overhead open position, substantially horizontal track means on the upper portion of said frame, roller means on said door adapted to run in said track means, a relatively long arm, means providing at one end of said arm an axis of turning therefor located to the rear of said door when the door is in closed position, spring means having one end associated with a stationary abutment disposed to the rear of said door when the door is in closed position and having the other end operatively associated with said door to assist in opening said door and means providing a pivotal connection between the outer end of said arm and said door including a slot and pin pivotal connection between the arm and

the door and operative when the door is in vertical position to permit movement of the pin vertically downwardly in the slot so as to remove the weight of the door from the arm together with means for preventing relative movement between the slot and the pin when the door is in overhead substantially horizontal position, said last named means comprising a stop lug disposed in the path of movement of the arm for preventing the pin from moving in the slot only when the door is in overhead substantially horizontal position.

12. In combination with an enclosure having a frame providing a door opening, a rigid door therefor adapted in closed position to lie substantially vertical and to shift to substantially horizontal overhead open position, substantially horizontal track means on the upper portion of said frame, roller means mounted on said door relatively close to the upper inner face of said door and adapted to run in said track means and comprising the sole support for said door when the door is in closed position, a relatively long arm, means providing at one end of said arm an axis of turning therefor located to the rear of said door when the door is in closed position, the other end of said arm being pivoted to a bottom portion of said door, a stationary abutment disposed at the rear of the door when the door is in closed position, spring means connected with the stationary abutment and having the other end operatively associated with the door to assist in opening said door, and means providing a pivotal connection between the outer end of said arm and said door, said arm and said track and roller means constituting the sole support means for the door when the door is in shifted position, said last named pivotal connection between the arm and door including means automatically shifting relative to the door to a position to remove the weight of the door from said pivotal connection when the door is in closed position, and including means for interlocking the arm and the door against relative shifting when the door reaches open position.
